CLAIM

The ornamental design for a wireless speaker, as shown and described.

DESCRIPTION

FIG. 1 is a left perspective view of a wireless speaker of the present disclosure;

FIG. 2 is a right perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The surface located inside of the broken line square on the bottom of the article forms no part of the claimed design. The four pentagonal feet located within the broken line square surface on the bottom of the article form part of the claimed design.

The broken lines shown in the drawings represent portions of the wireless speaker and form no part of the claimed design.

1 Claim, 8 Drawing Sheets
